UNITED STATES PATENT OFFICE.

LEWIS E. PARMELEE, OF HILLIARDS, MICHIGA

CUTTING-MACHINE.

1,165,119.

Specification of Letters Patent. Patented Dec. 21, 1915.

Application filed April 29, 1915. Serial No. 24,659.

To all whom it may concern:

Be it known that I, LEWIS E. PARMELEE, a citizen of the United States, and a resident of Hilliards, in the county of Allegan and 5 State of Michigan, have made certain new and useful Improvements in Cutting-Machines, of which the following is a specification.

My invention is an improvement in cutting machines, and the invention has for its 10 object to provide a machine of the character specified especially adapted for cutting standing corn and the like, wherein a wheeled support is provided, having cutting 15 mechanism at the front thereof for cutting the standing stalks in the row, and wherein a traveling feed table is provided arranged to carry the material from the cutting mechanism to other mechanism for cutting the 20 stalks into short lengths, suitable for ensilage, and wherein a motor is provided on the support for operating the cutting mechanisms and the feed table.

In the drawings: Figure 1 is a top plan 25 view of the improved cutting machine. Fig. 2 is a side view. Fig. 3 is a section on the line 3—3 of Fig. 2, looking in the direction of the arrow adjacent the line. Fig. 4 is an enlarged partial rear view showing the cutting and delivery mechanism, and Fig. 5 is a section on the line 5—5 of Fig. 4, looking in the direction of the arrow adjacent the line.

The present embodiment of the invention 35 comprises a platform or table 1, which is supported by rear wheels 2 and front wheels 3, the rear wheels being journaled on the ends of an axle 4, which is supported below the table 1, and the front wheels are jour- 40 naled on the ends of an axle 5.

A tongue 6 is connected with the axle 5, and the tongue is braced against the axle by inclined braces 7. The lower section of a fifth wheel 8 is mounted on the axle and the 45 tongue and the upper section 9 of the fifth wheel coöperating with the section 8 is connected to the front end of the table 1, by brackets 10, the brackets spacing the said upper section below the table.

50 A motor 11 is supported on the table, the motor being a gasoline engine in the present instance, and the piston of the motor is con-

nected by means of the rod 12 to the crank arm 13 of the crank shaft 14. Fly wheels 15 are secured to the opposite ends of the 55 shaft, and a pulley 16 is secured to the inner end of the shaft.

A belt 17 connects the pulley to a pulley 18 arranged on a shaft 19 near the rear of the frame. This shaft 19 is provided with 60 a gear wheel 20 which meshes with the gear wheel 21 on the shaft of a roller 21^a, to be later described, and arranged at the upper end of an endless carrier whose upper roller 22 is journaled between side plates 23 and 23^a of an elevator frame, the said frame consisting of the side plates and a bottom 25 connecting the side plates. A roller 24 is journaled between the side plates at the opposite end from the roller 22, and an endless 70 belt 26 is supported by the rollers 22 and 24. This belt is provided with transverse slats 27 at spaced intervals, and it will be noticed from an inspection of Fig. 2 that the carrier constituted by the belt inclines up- 75 wardly toward the rear end of the supporting frame. The shaft of the roller 22 is journaled in bearings 28 on the frame, and at its inner face the gear wheel 21 has a beveled gear 29. This beveled gear meshes 80 with a bevel pinion 30 on a shaft 31 extending longitudinally of the carrier just described, and at the inner side of the side plate 23, the said shaft being journaled in bearing brackets 32 extending inwardly from 85 the side plates. Near its lower end the shaft has a beveled gear 33 which meshes with a similar gear 34 on a counter-shaft 35 journaled transversely of the side plates 23 and 23^a.

The counter-shaft 35 is provided at each 90 end with sprocket wheels 36, and sprocket chains 37 connect the said wheels with other sprocket wheels 38 on the outer ends of stub-shafts 39. The stub-shafts are arranged 95 at opposite sides of the endless carrier 25, each being journaled in an extension plate 40 extending forwardly from the adjacent side plate 23 or 23^a, as the case may be. These plates 40 are triangular, as shown, and 100 the forward end of each plate is an acute angle.

The plates 40 are spaced apart, the same distance as the plates 23, 23^a, and cutting

mechanism for the corn in the row is arranged at the junction of the side plates with the plates 23, 23^a, and just in front of the lower end of the endless carrier, that is, just in front of the roller 24.

The cutting mechanism comprises a fixed channel-shaped guide 41 extending between the plates 40, and having its channel upward, and a sickle bar 42 is mounted to 10 reciprocate in the channel. Guard fingers 43 extend above the sickle bar and above the cutting knives 44, which are secured to the bar and extend outwardly therefrom. These knives, as shown, are the ordinary 15 triangular cutting knives, each having its apex forwardly and the sickle bar is operated by means of a pitman 45 connected at one end to the sickle bar and at the other end to a wrist pin 46 on a disk 47 secured 20 to the lower end of the shaft 31 before mentioned. It will be obvious that when this shaft 31 rotates, the sickle bar will be reciprocated in the guide and the standing stalks are guided into position to be cut by 25 the blades 44 by means of guide bars 48. These guide bars 48 are connected at their outer ends to the inner faces of the plates 40 and the bars converge inwardly toward the center of the endless carrier, the inner ends 30 of the bars being spaced apart the width of one of the cutting blades 44.

The stub-shafts 39 before mentioned are in alinement, and are at opposite sides of the endless carrier 25. Each stub-shaft carries a sprocket wheel 49 at its inner end and a sprocket chain 50 connects each of the sprocket wheels 49 with a wheel 51 journaled at the lower end of the adjacent side plate 48. Each sprocket chain 50 is provided with outwardly extending spurs or lugs 52, the lugs or spurs being spaced apart from each other as shown, and extending always perpendicular from the chain.

A guide or support 53 is arranged beneath the upper run of each of the chains 50 for supporting and guiding the said upper run, and the chains incline upwardly from the apices of the plate 40 toward their inner end, the said inner end being spaced 50 above the lower end of the endless carrier 25 some distance, as shown. The chains 50 are approximately parallel with the endless carrier.

The pitman 45 which operates the sickle bar extends through an opening or slot 54 in the adjacent plate 40, and the ends of the guide bars 41 have lateral extensions 55 which are secured to the inner faces of the plate 40. As the standing corn is cut it falls 60 upon the upper run of the endless carrier 26 and is carried upwardly to feed rollers which deliver it to the cutting mechanism. The lower feed roller 21^a before mentioned is journaled in standards 56 extending up-

wardly from the side plates 23 and 23^a, and an upper roller 57 is provided with a shaft 58 which is journaled at its ends in bearing blocks 59 mounted to slide in vertical guideways 60 in the standards or uprights 56. The bearing blocks are normally pressed 70 downward by springs 59^a which are arranged in the guideways between the bearing blocks and a connecting plate 60^a arranged transversely of the upper end of each guideway and of the adjacent upright. 75

The roller 57 normally runs in contact with the periphery of the roller 21^a and the said roller 21^a is just above and behind the roller 22. An inclined chute 61 is arranged in rear of the endless carrier 26, for receiving the material from the feed rollers, the upper end of the chute being just below the lower feed roller 21^a.

The chute decreases in width toward its rear end and the said rear end delivers to 85 an endless delivering carrier to be later described in detail.

The cutting mechanism is secured to the shaft 19, before mentioned, and the said shaft is journaled in bearing arms 62 connected to the side plates 23 and 23^a in rear of the uprights or standards 56. The said shaft is provided at the opposite end from the pulley 18 with a gear wheel 63, which meshes with a gear wheel 64 on the opposite 95 end of the roller 21^a, before mentioned, and the said roller 21^a is connected to the roller 22 by means of a sprocket chain 65, which connects sprocket wheels 66 and 67, respectively, on the shafts 22 and 21^a. Thus the 100 endless carrier 25 is driven by the sprocket chain 65 from the shaft 19.

The cutting mechanism comprises a substantially rectangular metallic frame consisting of side members 68 and connecting end members 69, and each end member is provided with a central hub 70 fitting over the shaft 19, and secured thereto by a key 71 and a set screw 72. The forward edges of the side members 68 are sharpened or beveled to form cutting edges, as shown more particularly in Fig. 5, and these movable blades 68 cooperate with a fixed ledger blade 73 arranged just in rear of the point of contact between the feed rollers. The rear edge of the fixed blade is perpendicular to the opposite faces of the blade, and it will be evident that as the movable blade 68 sweeps past the vertical edge, the stalks will be cut and will fall upon the chute 61 which 110 will deliver them to the endless carrier to be described. This carrier comprises side plates 74 and a bottom 75, and rollers 76 and 77 are journaled transversely of the side plates at the opposite ends thereof.

An endless belt 78 is supported by the rollers and slats 79 are secured to the belt transversely thereof at spaced intervals.

The upper run of the belt passes above the bottom 75, and the upper run of the belt 26 moves in like manner above the bottom 25. Thus the upper run of the belt 78 is supported by the bottom 75 of the frame. The ends of the shaft 76 are extended, as shown, and the said ends are journaled in bearings 80 in the arms of a yoke or U-shaped bracket 81. At its inner ends the shaft 76 is provided with a beveled gear 82 which meshes with a similar gear 83 on the lower end of a shaft 84 journaled in a bearing arm 85 at its upper end, which extends laterally from the adjacent bracket 62, and at its lower end 15 the shaft is journaled in a bearing bracket 86 connected to the adjacent side plate 23^a.

At its upper end the shaft 84 has a beveled pinion 87 which meshes with a beveled gear 88 integral with the pinion 63, before mentioned. Thus the roller 76 of the delivery carrier is driven by the shaft 19, and the said shaft drives also the endless carrier 25 and the sickle bar through the shaft 31.

A platform or table 89 is arranged on the side plate 23^a intermediate the ends thereof, and just below the feed table and extending from the said table to the inner ends of the chains 50. The side plate 23^a is provided with an extension 90 inclining outwardly and upwardly, as shown more particularly in Fig. 1.

The table 89 is supported by brackets 91 secured to the table and to the side plate 23^a. The axle 4 is connected to the platform 1 by brackets 10^a similar to the brackets 10, before mentioned.

In operation, the machine is drawn through the field by any suitable means, with the plates 40 on the opposite sides of the row of corn. As the machine advances through the field with the motor running, the stalks are guided into position to be cut by the knives or blades 44 on the sickle bar. The cut stalks fall upon the upper run of the endless carrier 25 and are carried rearwardly, being finally delivered to the feed rollers 21^a—57. The rollers feed the stalks rearwardly between the same and over the ledger blade 73, and as the stalks pass rearwardly behind the blade, they are cut or clipped into pieces by the blades 68. The cut stalks fall upon the chute 61, which delivers them to the endless carrier 78. This carrier is made adjustable so that the outer end may be raised or lowered, and the cut stalks may be delivered into a wagon or other vehicle, if desired, or they may be delivered on to the ground.

It will be noted from an inspection of Fig. 5 that the table 1 is provided with an opening 92 intermediate its ends, through which the endless carrier 25 extends. The front axle and connected parts form a truck at the front of the platform pivoted thereto

for permitting the wheeled support to be guided.

I claim:—

1. In a machine of the character specified, a wheel supported frame, an endless carrier at one side of the frame and extending downwardly at its front end, cutting mechanism at the front end of the endless carrier and intermediate the side edges thereof, vertical guide plates at opposite sides of the front end of the endless carrier, endless chains mounted on the guide plates and inclining upwardly toward their rear ends, guide bars extending inwardly from the front ends of the guide plates toward the cutting mechanism, a motor supported on the frame, and driving connections between the motor, the endless carrier, the chains and the cutting mechanism.

2. In a machine of the character specified, a wheel supported frame, an endless carrier at one side of the frame and extending downwardly at its front end, cutting mechanism at the front end of the endless carrier and intermediate the side edges thereof, vertical guide plates at opposite sides of the front end of the endless carrier, endless chains mounted on the guide plates and inclining upwardly toward their rear ends, and guide bars extending inwardly from the front ends of the guide plates toward the cutting mechanism.

3. In a machine of the character specified, a wheel supported frame, an endless carrier supporting trough at one side of the frame and inclining downwardly toward its front end, an endless carrier supported by the trough, cutting mechanism at the said front end, moving means for guiding the stalks to the cutting mechanism, cutting mechanism at the upper end of the carrier for cutting the stalks into lengths, an endless carrier arranged transversely of the rear of the frame, a shaft upon which the inner end of the carrier is journaled, said shaft being journaled on the frame, a motor on the wheel supported frame, driving connections between the motor, the endless carrier, the first named cutting mechanism and the moving mechanism for the stalks, a vertical shaft journaled on the frame at the rear thereof and having a driving connection with the shaft upon which the transverse carrier is mounted, and having a driving connection with the stalk cutting mechanism, and means for swinging the carrier on its supporting shaft.

4. In a machine of the character specified, a wheel supported frame, an endless carrier mounted at one side of the frame and inclining downwardly toward its front end, a shaft journaled at the upper end of the carrier for supporting and driving the same, a vertical shaft journaled on the frame at

one end of the said shaft and having a driving connection therewith at its upper end, a shaft journaled on the frame at the lower end of the vertical shaft and having a driving connection with the said shaft, an endless carrier supported at one end by the last named shaft and driven by the said shaft, cutting mechanism at the front of the first

named endless carrier, a shaft journaled longitudinally of the said endless carrier and having a driving connection with the cutting mechanism at its front end and with the first named shaft at its rear end, and means for driving said shaft supported by the frame. 10

LEWIS E. PARMELEE.
